UNITED STATES PATENT OFFICE.

JAMES I. NORTH, OF BALTIMORE, MARYLAND.

COLLAR.

Application filed February 3, 1925. Serial No. 6,521.

To all whom it may concern:

Be it known that I, JAMES I. NORTH, a citizen of the United States of America, residing in the city of Baltimore, State of Maryland, have invented certain new and useful Improvements in Collars, of which the following is a specification.

The invention relates to a shirt collar which may be attached to the shirt or a separate attachable collar, the object of the invention being the production of a collar which will maintain its shape and have the appearance of a laundered starched collar without the use of starch or any equivalent material, thus avoiding the rigidity and discomfort incident to the use of starch in this connection without sacrificing the neatness, style and appearance of dressiness which goes with a well-laundered starched collar, and at the same time making it feasible to use in the outside of the flap and other visible portions of the collar the same material as that of which the shirt is constructed, a requisite of the present styles not met by the semi-soft collars made of a single thickness of an inherently stiff fabric.

More particularly the device of the invention comprises a collar having in the flap or band, a lining of fabric which possesses sufficient inherent rigidity to maintain the shape of the collar without the use of starch or other equivalent stiffening agent. This material is referred to herein as composed of spun fibres of water-absorbent material, meaning that it is a fabric composed of textile fibres in common use. The fabric referred to having the interwoven multiple-ply so woven as to have the necessary effect in supporting the collar is not sensitive to moisture in that it does not shrink or become distorted when wet and it is sufficiently resilient to cause the collar to regain its shape when distorted.

The stiffening lining must be a fabric having the necessary degree of stiffness. The two or three ply fabrics which have long been used as the stiffening element in various garments, have been found by this inventor to be very effective in this capacity. They impart to the collar the desired degree of stiffness without starching.

In the accompanying drawing I have illustrated a collar embodying the features of my invention in the preferred form.

In the drawing—

Figure 1 is a perspective view of a separate collar made in accordance with the invention.

Figure 2 is a sectional elevation of a collar having the stiffening material in the band the section being taken on line 2—2 of Fig. 1.

Figure 3 is an elevation of a band of stiffening material cut in the pattern to be used in this collar.

Figure 4 is a section of a collar having the stiffening lining in the flap and attached to the shirt.

Figure 5 is an elevation of a stiffening lining adapted to the collar shown in Figure 4.

Referring to the drawings by numerals, the collar as shown in Figures 1, 2 and 3 comprises a neck-band 1 and a flap 2. The band 1, as shown, comprises an inner facing 4 and an outer facing 5 which may be of the same material as the shirt, to which it may be attached or from which it may be separate, being attachable by means of studs according to the particular preference of the trade at the time of manufacture. In the form of collar shown in Figure 2, the band includes a lining 6 of a fabric which is of sufficient rigidity without starch to maintain the shape and position of the band and hence of the collar when the shirt is worn without the use of starch or other equivalent stiffening agent. This may to advantage be a stiffening fabric of a plurality of plies or thicknesses suitably interwoven in accordance with the well-known practice in the production of stiffening fabrics. The inner and outer facings 4 and 5 are turned inwardly at the top and bottom. The stiffening lining 6 in the form shown is laid in registration with the outer facing 5 and turned in therewith at both edges 6', 6'', the combined hems 7, 7'' at the bottom and the neck of the shirt 18 inserted between these hems if it is an attached collar being

sewed through and through by and with the edge seam 7 which extends along the bot-

tom circumference of the band. At the top the top edges 8 of the flap are placed between the inturned edges 8' and 8'' of the band facings 4 and 5, and sewed with a circumferential seam 9 and preferably the entire neckband of the collar is sewed through and through with a plurality of circumferential seams 10 spaced apart vertically across the entire width of the band. These 10 seams prevent buckling on account of the shortened circumference of the inner facing of the collar when it is closed about the neck of the wearer. Either or both the facings 4 and 5 may be like the shirt or of plain 15 material.

The flap 2 comprises an inner and outer facing 14, and 15, either or both of which may be of the same material as the shirt or plain, the collar being attached or separate, 20 and it is shown as lined with a thin fabric 16. It is not regarded as necessary to stiffen both the band and the flap, the stiffening in either member being sufficient.

In the construction of the outer flap, both 25 the inner facing 14 and the outer facing 15 are turned in along the bottom circumferential edges and along the front edge 17, and the lining 16 which overlies or registers with the inner facing 14 is turned in with the 30 inner facing, and the inturned edges are sewed through and through by a bottom and front edge seam 18. The top edges 8 of the three thicknesses of the fabric 14, 15, 16 are, as already stated, inserted between the 35 inturned edges of the band and sewed through and through by the top circumferential seam 9.

The stiffening member 6 of the band may 40 to advantage be further reinforced by means of a strip of tape or other material 19 extending along the band and around the circumference of the collar and stitched thereto by longitudinal seams 20 extending along its edges. This gives additional stiffness.

45 In Figure 4 I have illustrated a collar having the stiffening in the flap 2 instead of in the band 1. This collar is constructed substantially the same as that illustrated particularly in Figure 2, except that the 50 neckband 1 is preferably not stiffened, having its inner facing 4 and its outer facing 5 of any suitable fabric which may be the same as that of the shirt with which it is to be used, the lining 20 being of any suitable thin material as is the lining 16, Figure 2. The top and bottom edges of the neck band are turned in, the neck or yoke of the shirt 21 being sewed to the outer facing of the collar by a seam 22 and the outer 55 facing being then turned up, giving the effect of turning in the edge 7" of the outer facing. The inner facing 4 and the lining 20 are turned in together at 7" and 20" and sewed to the edge of the neck of the shirt 21 60 by a seam 23. However, the exact construc- 65

tion is not material. At the top the lining 20 is turned in at 20' with the inner facing, the inturned portion of which is indicated by 8'. The outer facing is likewise turned in at 8'', and the top edges of the flap 2 indicated by 8 are inserted between the two sets of inturned edges and the entire overlapping portion thus described is sewed through and through by the top circumferential seam 9. The flap is formed of an inner flap facing 70 14 and an outer flap facing 15 which may be of any suitable material, and usually of the same material as that of which the shirt is constructed, and a stiffening lining 26 75 of a nature to impart to the outer flap a 80 sufficient degree of stiffness to cause it to stand up when laundered without starching or equivalent treatment. This may be of fabric of a plurality of thicknesses or plies 85 suitably interwoven in accordance with the well-known practice in the manufacture of stiffening fabric used in various garments.

The outer flap is finished at the bottom at 18 in any suitable manner. The inner facing 14 is first placed in registration with the 90 outer facing 15 and the two sewed together along the bottom edge by the seam 24. As shown the stiffening fabric 26 is cut to the shape of the facings 14 and 15 and placed in registration with them, the bottom edges 95 14', 15' and 26' being turned in together. The inner facing 14 is then turned over and all three fabrics having been turned in at the bottom edge 18, the inturned portions and the main portion of the fabric forming 100 six layers are sewed through and through along the bottom edge by the seam 18, and the top edges inserted in the band as above described.

The details of construction thus recited 105 may of course be widely varied. Both forms of collar thus described may be made to the best advantage as to the external portions or facings, of the fabric of the shirt with which they are to be used or to which they 110 are attached, making it feasible to provide in connection with the various shirts of fabrics either white or colored which are almost universally worn, a collar of the fabric identical with the shirt, which stands up 115 and presents without starching the neat appearance of a starched laundered collar without the discomfort incident to starched apparel, an advantage which is not incident to the popular unstarched and so-called semi-soft collars having the flap made of a single ply of stiff fabric known as the semi-soft collar, as such collars cannot be made of fabric like the shirt.

I have thus described specifically and in 120 detail a single embodiment of my invention in order that the nature of the same and its use may be clearly understood; however, the specific terms herein are used descriptively 125 rather than in a limiting sense, the scope of 130

the invention being defined in the claims. The words "shirt collar" in the claims refer to an attached or detached collar to be attached to the shirt.

5. What I claim and desire to secure by Letters Patent is:

1. The combination with a shirt of soft unstarched material of an attached collar having a neckband with a lining of a fabric 10 of a plurality of interwoven plies which causes the collar to stand up and retain its shape without starch, the band being covered as to all exposed portions with the material of which the shirt is made, and sewed 15 through and through with a series of seams placed side by side and extending longitudinally of the neckband and circumferentially of the neck of the shirt, the collar also having a flap composed externally of the 20 same shirting fabric.

2. The combination in a soft shirt of an attached collar having a resilient inner lining 25 support of multiple-ply textile fabric which causes the collar to stand up and retain and maintain its shape without starching, the collar being formed as to substantially all portions of its external surface of a fabric identical with that of the shirt.

3. A shirt collar having a neckband with

a lining of a fabric of a plurality of interwoven plies which causes the collar to stand up and retain its shape without starch, the band being covered as to all exposed portions with a single ply fabric, and sewed through and through with a series of seams placed 30 side by side and extending longitudinally of the neckband and circumferentially of the neck opening of the shirt.

4. The combination with a shirt of soft unstarched material, of a collar having a neckband with a lining of water-absorbent resilient textile fabric formed mainly of spun fibres, which fabric does not shrink or lose its shape when wet and which causes the collar to stand up without starching and to regain its shape when distorted, the band being covered as to all exposed portions with the material of which the shirt is made, and sewed through and through with a series of lines of stitching placed side by side 40 throughout the entire width of the band and extending longitudinally of the neck-band and circumferentially of the neck of the shirt, the collar also having a flap composed externally of the same shirting fabric. 45

Signed by me at Baltimore, Maryland, this 2 day of February, 1925.

JAMES I. NORTH.
